UNITED STATES PATENT OFFICE

92,577

DESIGN FOR A GAS RANGE

William T. Bradbury, Kankakee, Ill., assignor to
Florence Stove Company, Gardner, Mass., a cor-
poration of Massachusetts

Application March 29, 1934, Serial No. 51,239

Term of patent 7 years

To all whom it may concern:

Be it known that I, WILLIAM T. BRADBURY, a citizen of the United States, residing at Kankakee, in the county of Kankakee, and State of Illinois, have invented a new, original, and ornamental Design for a Gas Range, of which the following is a specification, reference being had to the accompanying drawing, forming part thereof.

The figure is a perspective view of a gas range showing my new design.

I claim:

The ornamental design for a gas range substantially as shown.

WILLIAM T. BRADBURY.
